PANEL FOR A LAUNDRY APPLIANCE OR THE LIKE

Stuart G. Mundt, Syracuse, N. Y., assignor to
Easy Washing Machine Corporation, Syracuse,
N. Y., a corporation of Delaware

Application October 22, 1953, Serial No. 27,285

Term of patent 14 years

(Cl. D49—1)

To all whom it may concern:

Be it known that I, Stuart G. Mundt, a citizen of the United States of America, residing at Syracuse, in the county of Onondaga and State of New York, have invented a new, original, and ornamental Design for a Panel for a Laundry Appliance or the like, of which the following is a specification, reference being had to the accompanying drawings, forming part thereof, in which:

Figure 1 is a front elevational view of a panel for a laundry appliance or the like, showing my new design;

Figure 2 is a top plan view;

Figure 3 is a transverse sectional view on an enlarged scale, taken on the line 3—3 of Figure 1; and

Figure 4 is a transverse sectional view on an enlarged scale, taken on the line 4—4 of Figure 1.

I claim:

The ornamental design for a panel for a laundry appliance or the like, substantially as shown.
